UNITED STATES PATENT OFFICE

155,925

DESIGN FOR A CLOTHESPIN

James H. Robertson, Redwood City, Calif.

Application February 1, 1947, Serial No. 136,624

Term of patent 7 years

(Cl. D17—6)

To all whom it may concern:

Be it known that I, James H. Robertson, a citizen of the United States, residing at 28 Diller Street, Redwood City, State of California, have invented a new, original, and ornamental Design for a Clothes Pin, of which the following is a specification, reference being had to the accompanying drawing, forming a part thereof.

Fig. 1 is an elevational view of a clothes pin, showing my new design as viewed from one lateral edge thereof;

Fig. 2 is a side elevational view, the opposite side being identical with the one shown; and

Fig. 3 is an elevational view of the lateral edge opposite to that shown in Fig. 1.

The diagonal shading shown on Fig. 2 represents a knurled surface and is carried over both sides of the clothes pin in the manner as indicated.

I claim:

The ornamental design for a clothes pin, as shown and described.

JAMES H. ROBERTSON.
